UNITED STATES PATENT OFFICE.

GILLES HOLST AND EKKO OOSTERHUIS, OF EINDHOVEN, NETHERLANDS, ASSIGNEES
TO NAAMLOOZE VENNOOTSCHAP PHILIPS' GLOEILAMPEN-FABRIKEN, OF EINDHOVEN, NETHERLANDS, A LIMITED LIABILITY COMPANY OF THE NETHERLANDS.

VACUUM TUBE.

1,410,756.

Specification of Letters Patent. Patented Mar. 28, 1922.

Application filed March 30, 1921. Serial No. 457,146.

To all whom it may concern:

Be it known that we, GILLES HOLST and EKKO OOSTERHUIS, subjects of the Queen of the Netherlands, residing in Eindhoven, in the Province of North-Brabant, Kingdom of the Netherlands, have invented certain new and useful Improvements in Vacuum Tubes, (for which we have filed applications in the Kingdom of the Netherlands, Aug. 30, 10 1918; Germany, Jan. 21, 1919; England, Feb. 5, 1919; Italy, June 28, 1920; Spain, June 22, 1920; Czecho-Slovakia, Feb. 9, 1921), of which the following is a specification.

15 It is known, that the gas contents of vacuum tubes, such as Röntgen tubes or Geissler tubes, or tubes for the Moore light, etc., disappear under the influence of the electric discharge. The tube thereby becomes harder, the passage of the current becomes more difficult and finally stops altogether. Therefore, several kinds of apparatus have been devised to automatically renew or complete the gas in the tube. One 20 of these apparatus is the Bauer valve. It consists of a glass capillary tube, partly filled with mercury. To this capillary tube a small side tube is attached, containing a small porous plug. With a small air-pump, 25 the mercury may be forced past the porous plug, so that air passes into the vacuum tube. This device, therefore, is not automatic and is only able to force air into the tube.

30 The present invention relates to a similar device in which however, the filling can take place automatically, as soon as the hardness of the tube exceeds a definite degree, and by which any gas may be brought 35 into the vacuum tube.

In the accompanying drawings,

Figure 1 is a section of a Bauer valve,

Figure 2 is a section of a construction according to the invention, and

40 Figure 3 shows diagrammatically the apparatus according to the invention, connected to a vacuum tube.

Figure 4 is a fragment of Fig. 2, showing a modification.

45 The Bauer valve shown in Fig. 1 comprises a tubular vessel *d* having at *b* a connec-

tion to the vacuum tube, with a mercury tube *k* sealed into it at *m* with its end *n* open to the atmosphere, and at *q* a branch tube opening into *d* and sealed by a porous plug *p* which is impermeable to mercury but permeable to gas. With a sufficient vacuum in the vacuum tube, the mercury is forced down by the atmospheric pressure until it uncovers the plug, whereupon air enters 60 through the porous plug into *d* and through *b* into the vacuum tube.

The apparatus according to this invention (see Fig. 2) consists of a gas reservoir *a*, in which there is a heating means whereby the 65 gas in *a* may be heated by an electric current. The heating device may consist for example of two electrodes (as shown in Fig. 2), or of an incandescent filament (as shown in Fig. 4). When the current passes, the 70 gas will expand and thereby press the mercury column *k* in the capillary tube *c* downwards. At *p* is a porous plug impermeable to mercury but permeable to gas. When the pressure in *a* becomes so high that the 75 mercury is forced below *p* a small quantity of gas will diffuse through the porous plug and pass through the tube *b* into the vacuum tube.

To obtain automatic working one may 80 proceed in any usual way.

The Röntgen tube shown in Figure 3 is connected to a source of electricity. One of the electrodes in *a* is connected to the anode, the other is connected to a wire or a small 85 bar which is placed at a suitable distance from the cathode. As soon as the Röntgen tube becomes too hard, the electric current will pass through *a* and heat the gas therein. The mercury is forced past the porous 90 plug, so that a small quantity of gas diffuses into the Röntgen tube. Thereby the latter becomes softer and the discharge will again take place in the normal way.

An advantage of the device described is 95 that any desired gas can be passed into the vacuum tube because the reservoir *a* is completely closed.

What we claim is:—

1. A device for introducing gas in a 100 vacuum tube, comprising a reservoir containing gas, having within it means for elec-

- trically heating the gas, and a mercury tube connecting with the reservoir and having a porous plug connection with the interior of the vacuum tube.
- 5 2. A device for introducing gas in a vacuum tube, comprising a reservoir containing gas, having within it two electrodes for heating the gas, and a mercury tube connecting with the reservoir and having a porous plug connection with the interior of the vacuum tube.
- 10

In witness whereof, we have hereunto signed our names in the presence of two subscribing witnesses.

GILLES HOLST,
EKKO OOSTERHUIS.

Witnesses:

HENDRICUS JAMPS,
ALPHONSO DE BRUT.

Certificate of Correction.

It is hereby certified that the assignee in Letters Patent No. 1,410,756, granted March 28, 1922, upon the application of Gilles Holst and Ekko Oosterhuis, of Eindhoven, Netherlands, for an improvement in "Vacuum Tubes," was erroneously described and specified as "Naamlooze Vennootschap Philips' Gloeilampen-Fabriken, of Eindhoven, Netherlands, a Limited Liability Company of the Netherlands," whereas said assignee should have been described and specified as *Naamlooze Vennootschap Philips' Gloeilampen-Fabrieken, of Eindhoven, Netherlands, a Limited Liability Company of the Netherlands*, as shown by the records of assignments in this office; and that the said Letters Patent should be read with this correction therein that the same may conform to the record of the case in the Patent Office.

Signed and sealed this 20th day of June, A. D., 1922.

[SEAL.]

KARL FENNING,
Acting Commissioner of Patents.
